ELECTROMAGNETIC RELAY

Otto Dreyßen, Berlin-Friedenau, Germany, assignee to Mix & Genest Aktiengesellschaft, Berlin-Schöneberg, Germany

Application May 6, 1931, Serial No. 535,369
In Germany May 17, 1930

7 Claims. (Cl. 200—83)

This invention relates to electromagnetic relays of the kind in which the armature is not suspended from a yoke but is lying in its position of rest as an independent member.

5 The main feature of the invention is that such armature is disposed within the exciting coil, the relay thus occupying as little space as possible, and that the path of the magnetic flux of this coil is so governed as to secure a reliable action
10 on the armature.

The invention will be fully understood from the following description and be particularly pointed out in the appended claims, reference being had to the accompanying drawing in which—

15 Fig. 1 is a section view of one embodiment.
Fig. 2 shows a section on the line 2—2 of Fig. 1.
Fig. 3 is a plan of this device.

20 Fig. 4 is a section of a modification of the arrangement represented by Figs. 1 to 3.
Fig. 5 is an end elevation, partly in section, of still another modification.

25 Like numerals of reference denote like parts in the several views.

1 indicates exciting coils. 2 denotes the armatures. 3 indicates U-shaped bodies of iron or like material adapted to conduct magnetic lines of force. By 4, 5, 6, 7 terminals of electric circuits are denoted. One of these circuits is represented in Fig. 1 by wires 8 soldered to the terminals 4,

30 5. The armatures 2 are to make and break contact with such terminals so as to close or open the said circuits. The terminals 4 to 7 are fitted in insulating bars 9 and are insulated from the bodies 3 by paper, pasteboard or the like 10. Screws 11 are holding the parts together, as will be seen from Figs. 1 and 4.

35 In the construction shown in Figs. 1 to 3 there are two coils 1 fixed by the screws 11 to the same body 3. The frame of either coil has three chambers 12. Each chamber 12 contains an armature 2 lying on the bottom thereof when in its position of rest. The body 3 is provided with a slot 13 in either of its lateral portions. Fig. 2 shows 40 one of these slots. The bars 9 are arranged to form also a guide for the armatures 2.

45 Whenever a current is caused to pass through one or the other of the coils 1, or through both of them, the body 3 being of soft iron or the like will take up the magnetic lines of force of the energized coils so as to gather these lines of force for a concentrated action on the armatures 2. In this way either three or all the six armatures 2 according to whether one or both of the 50 coils are energized, are operated to make contact

with the terminals 4, 5 so as to close the associated electric circuits. The armatures fall back into their positions of rest as soon as the coils are deenergized. The slot 13 is to prevent the coils from influencing each other.

55 Fig. 4 shows two bodies 3. The lower one is a permanent magnet so as to present a north pole N and a south pole S. The armature 2 of each chamber 12 when in its normal position rests upon two terminals 6, 7 so that the associated circuit is in a closed condition.

60 In order to operate the armature 2 the current passed through the coil 1 must be of such a direction that at the terminal 6 a north pole and at the terminal 7 a south pole is produced in the armature to overcome the attraction the magnetic poles N, S are exerting on the armature. If the current supplied to the coil flows in the other direction there will be produced in the armature a south pole at 6 and a north pole at 7 so as to increase the force with which the armature under the influence of the poles N, S adheres to the terminals 6, 7. This relay thus responds to currents of a definite direction only.

65 A modification of the arrangement illustrated in Fig. 4 can be created by substituting also the upper body 3 by a permanent magnet. This second magnet is so disposed that the south pole thereof is at the terminal 4 and consequently the north pole located at the terminal 5. This modification can be readily imagined from Fig. 4 and therefore is not shown. As explained with reference to Fig. 4, the armature 2 will be raised if the current passed through the coil 1 flows in a definite direction. As soon as raised, the armature is attracted by the upper magnet 3 and is held in this position so as to maintain the closure of the circuit of the terminals 4, 5. This relay thus needs no locking circuit and can be operated by impulses. It can, for instance, be actuated by means of condensers. A current flowing in the other direction through the coil 1 will act to bring the armature back into the normal position.

70 In the construction shown in Fig. 5 two bodies 3 are provided as in Fig. 4. These, however, are furnished on either lateral portion with a current coil 15. These coils are separate from each other so that in each of the ends a, b, c, d, of the bodies 3 either a north pole or a south pole can be produced, depending upon the direction in which the currents are caused to flow through the coils 15. The bodies 3 are connected at their 75 middle portions by a magnetically conducting bridge 14.

If at *a* and *d* south poles, at *b* and *c* north poles are generated then the operation is the same as in the case of the arrangement shown in Fig. 4, if the upper body 3 of this arrangement is a permanent magnet as described.

If, however, north poles are produced, for instance, at *a* and *b*, and south poles generated at *c* and *d*, then the following operation takes place: The current passed through the coil 1 will polarize the armature 2 in accordance with the direction in which it flows, as is the case also in the constructions shown in Figs. 1 to 4.

This direction be such, for example, as to produce a north pole at the terminal 6 and a south pole at the terminal 7. The armature is consequently attracted at *c* and repelled at *d* so as to assume a diagonal position in which it connects the terminals 5, 6 with each other.

If on the contrary the current, exciting coil 1, flows in the other direction so as to generate in the armature a south pole at 6 and a north pole at 7, then the armature is attracted at *d* and repelled at *c*, thus taking up a diagonal position in which it connects the terminals 4, 7 to one another.

This relay is in this way adapted for operations that can not be effected by means of the known devices.

While each chamber 12 is shown to contain only one armature 2, a number thereof may be fitted in each chamber. Such modification can be readily imagined from Fig. 4 or 5 and is, therefore, not illustrated. It may consist, for instance, in a multiple provision of the parts 2 and 4 to 7, the groups composed of these parts being disposed above or below each other. An arrangement of this kind allows of controlling a larger number of electrical circuits than is the case in the constructions represented.

It is to be understood that still other details of the constructions disclosed may be varied within the scope indicated by the appended claims, without departing from the spirit or sacrificing any of the advantages of this invention.

What is claimed is:

1. In an electromagnetic device the combination of a channel-shaped magnetic conducting body, a plurality of exciting coils supported by said body with the coils positioned in the channel in spaced relation, each coil having a plurality of armatures arranged side by side and located therein, and means for making electrical contact with said armatures, the side walls of said

55

channel-shaped member being slotted between adjacent coils thereby to prevent each coil from influencing adjacent coils.

2. In an electromagnetic relay, a channel-shaped frame of magnetic material, an insulating spool supported by said frame and positioned between the walls thereof and having centrally disposed openings, an exciting coil carried by said insulating spool, armatures disposed in said openings, an insulating member secured to each wall of the channel-shaped member, a contact terminal for each armature carried by each insulating member, said insulating members being disposed opposite said openings so as to serve as guides for their armatures.

3. In an electromagnetic relay the combination of the exciting coil with an armature located within this coil and movable in a plane parallel to the axis of the coil, means adapted for electric contact with such armature, and magnetic means disposed in the magnetic flux of the said coil and adapted for a variable polarizing effect on said armature.

4. In an electromagnetic relay, the combination of an exciting coil having an opening extending therethrough, upper and lower contacts extending into said opening and parallel to the axis of said coil, and an armature extending through said opening normally resting upon said lower contacts.

5. In an electromagnetic relay, the combination of an exciting coil having an opening extending therethrough, a set of contacts extending into said opening, and an armature extending through said opening parallel to the axis of said coil and normally resting upon said contacts.

6. In an electromagnetic relay, the combination of an exciting coil wound upon a spool, insulating members covering the ends of said spool, an armature extending through the opening of the spool and movable in a direction parallel to the axis of the spool, and contacts extending through said insulating members engageable by said armature.

7. In an electromagnetic relay, an exciting coil having an opening extending therethrough, a plurality of separately excited magnetic conductors, contacts extending into the opening of said coil, an armature freely disposed within said opening, and means for exciting said separately excited conductors whereby said armature selectively engages said contacts.

OTTO DROYSEN.
